PRODUCTION OF ALKALI METAL
PEROXIDES

Georg Pfleiderer, Ludwigshafen-on-the-Rhine,
Germany, assignor to I. G. Farbenindustrie Aka-
tiengesellschaft, Frankfort-on-the-Main, Ger-
many

Application May 25, 1935, Serial No. 23,448
In Germany May 30, 1934

14 Claims. (Cl. 23—184)

The present invention relates to a process of producing alkali metal peroxides.

It is already known that by oxidizing with gaseous oxygen hydrazobenzene in alcoholic solution containing alkali, alkali metal peroxides are precipitated. It has also been proposed to prepare hydrogen peroxide by oxidizing a solution of hydrazobenzene in benzene with oxygen under pressure, reducing the resulting azobenzene to hydrazobenzene again and employing the latter again for oxidation. Certain other organic compounds which contain in the molecule two hydrogen atoms which can be split off comparatively readily, such as indigo white or anthrahydroquinone, i. e., so-called leuco-compounds have in a similar manner to hydrazobenzene.

I have found that alkali metal peroxides can be obtained by passing an alkaline solution of compounds of the said kind, i. e., an alkaline organic solution of an organic leuco-compound which is auto-oxidizable in alkaline solution and the auto-oxidation product of which is soluble in the solvent used, advantageously of hydrazobenzene, preferably in an alcohol, as for example 25 ethyl alcohol, in a cycle while alternately oxidizing with oxygen or gases containing oxygen, as for example air and reducing again, the precipitated peroxides being separated between the two operations and the substances removed from 30 the solution (alkali and in some cases water) being replenished continuously or periodically. By using sodium, for example, as the alkali metal, peroxides the composition of which corresponds substantially to the formulae $Na_2O_2 \cdot 8H_2O$ and 35 $NaHO_2$ or, more usually, between the two, are obtained depending on the working conditions and the water content of the alcohol employed.

The reaction of gaseous oxygen on hydrazobenzene in the presence for example of sodium alcoholate in alcoholic solution at ordinary or moderately elevated temperature and at atmospheric or increased pressure may be seen from the following equations which indicate the said two boundary cases:

45 (a) With several per cent water content in the solution

50 (b) With a very small water content in the solution

55 In order to reproduce hydrazobenzene from the

resulting azobenzene, it is preferable, among the various known methods of reduction to use alkali metal amalgam the alkali metal content of which is continuously replenished electrolytically in a second cycle. When working with 5 sodium, this proceeds according to the equation:

Just as much sodium is introduced into the 10 solution as is used up in the oxidation according to (a) so that there is the advantage that the necessary replenishment of sodium is effected at the same time as the reduction. In order to 15 keep the composition of the solution constant, water may also be added if necessary.

If the oxidation, by corresponding selection of the water content, proceeds according to equation (b) or by a reaction lying between (a) and (b), too much sodium passes into the solution as the result of the reduction with sodium amalgam and this excess becomes greater and the alkalinity constantly increases. The excess of alkali may be precipitated by suitable precipitants, as for example in the form of sodium 25 carbonate by means of carbon dioxide. It is more preferable, however, in the said case to effect the reduction partially by another method and only to use sodium amalgam for reduction to such an extent as corresponds to the amount of sodium 30 precipitated with the peroxide. This may be effected for example by dividing the oxidized solution into two parts after separation of the peroxide formed, reducing one part with sodium amalgam and the other for example with metallic zinc or directly by electrolysis or the well-known reduction with hydrogen in the presence of catalysts, and then reuniting the two parts. Both methods of reduction may also be employed 35 consecutively with the undivided solution.

40 By reason of the fact that the complete separation of the solid peroxide after the oxidation requires some time, it is preferable to allow the solution to stand between its oxidation and the separation of the precipitate.

45 The concentration of the single components in the solution may be varied within wide limits. The concentration of hydrazobenzene and like compounds is preferably kept somewhat below the saturation limit. For example an about 2 50 per cent alcoholic solution of hydrazobenzene has proved very suitable. The alkalinity may also be of different degrees but the ratio of sodium to hydrazobenzene or like compound in the reduced solution should at least correspond to the amount 55

of sodium required according to the equations (a) and (b). It is preferable to employ a from 0.3 to 1.5 normal alkaline solution. The water content of the solution amounts to several per cent, preferably for example from about 4 to 8 per cent, when working according to equation (a), and at the most about 1 per cent when working according to equation (b).

The final product, after having been washed 10 with alcohols or other suitable organic solvents, as for example carbon tetrachloride, and dried, is a white crystal powder which may be employed in the same way as alkali metal peroxides prepared by dry methods as an oxidizing agent, as 15 an agent supplying oxygen or as an initial material for the preparation of other percompounds, such as hydrogen peroxide, perborates, percarbonates and persulphates.

The nature of the invention will now be further described with reference to the accompanying 20 drawings but the invention is not restricted to the particular arrangements shown therein.

An arrangement suitable for carrying out the cyclic process already described is shown diagrammatically in Figure 1. Figure 2 shows a cross section of an intermediate container and its connecting pipes and the further devices connected therewith.

The alkaline hydrazobenzene solution is 30 brought into intimate contact with oxygen, for example by means of a stirrer, in the oxidation container O. The solution with the precipitated peroxide then flows through a wide pipe into an intermediate container B which is kept approximately full by an outlet valve V which is 35 preferably actuated automatically. The suspension passes thence into a centrifuge Z for the separation of the peroxide. The solution freed from precipitate is then passed by means of 40 pump P to a reservoir A. It then passes from the reservoir A into the reduction vessel R in which it is brought into intimate contact with liquid sodium amalgam. The separation of the solution from the amalgam takes place in the 45 settling tank C; this separation may be assisted by providing several such tanks and suitable filters. The reduced solution which has been freed from amalgam then flows again into the oxidation container O and the process recommences. 50 The water used up is replenished at a suitable point in the cycle. The sodium amalgam flows from C into an electrolytic cell E where the sodium content is replenished and then passes again into R. The stirrer in the reduction vessel R 55 serves at the same time as the means for promoting circulation of the amalgam because by its centrifugal action the amalgam is raised. Naturally, a special circulating pump may also be used for circulating the amalgam, and the means 60 used in the process for mixing, separating and circulating may be varied in different ways. In order to avoid too great a dilution of oxygen in the oxidation container O by the gradual enrichment of foreign gases, a small amount of 65 residual oxygen is preferably continuously withdrawn from the upper part of the container O.

By reason of the fact that the precipitated peroxide has a tendency to adhere to the walls of the vessels and pipes, the containers O and 70 B are preferably arranged as rotary bodies and provided with rotary scrapers which brush the walls and which either rotate slowly continuously or may be operated by hand. The short and wide connecting pipes between O and B and 75 between B and Z may also be provided with

scrapers and in this case they may consist for example of scraping rings or pistons which are displaceable in an axial direction.

Figure 2 shows an arrangement of the said kind applied to the container B and its connecting pipes. The inner wall of the container B which lies below the level of the liquid is brushed by a stripping frame a which may be rotated by a hollow axle b and which is mounted at the bottom in an open guide ring c. Special spring elements, which scrape the walls, may be provided on the frame a. The connecting pipe with the container O is kept free by means of an open stripping ring e moved backwards and forwards by means of a rod d and the connecting pipe 10 with the centrifuge Z is kept free by the stripping ring f secured on the rod g. By the bevelled guide portion h, the stripper may directly force the automatic valve V to the side. In order that the connecting pipe may not be fully open meanwhile, the ring F is wholly or partly closed by a horizontal disc. To facilitate the upward and downward movement of f, the weight of the rod g and, in particular, the pressure of the column of liquid when f is in the connecting pipe are 15 approximately counteracted by the counterweights p and P'. 20

The manner in which the automatic valve V acts as a weight-loaded pinch-valve (pivot point at k) may be clearly seen from the drawings. 30 A portion of the connection between B and Z is made from a wide comparatively flexible rubber tube which is preferably protected externally by a layer of fabric.

What I claim is:

1. The process of producing alkali-metal peroxides which comprises passing a solution of an alkali alcoholate and of an auto-oxidizable organic leuco-compound of the class consisting of hydrazobenzene and anthrahydroquinone in a 40 cycle while alternately oxidizing with gaseous oxygen and reducing again partly with alkali-metal amalgam and partly with a reducing agent containing no alkali and no alkali-metal, the precipitated peroxides being separated between the 45 two operations and the substances removed from the solution being replenished.

2. The process of producing alkali-metal peroxides which comprises passing a solution of an alkali alcoholate and of an auto-oxidizable organic leuco-compound of the class consisting of hydrazobenzene and anthrahydroquinone in a cycle while alternately oxidizing with gaseous oxygen and reducing again partly with alkali-metal amalgam and partly by the well known reduction with hydrogen in the presence of catalysts, the precipitated peroxides being separated between the two operations and the substances removed from the solution being replenished.

3. The process of producing alkali metal peroxides which comprises passing a solution of an alkali alcoholate and of an organic leuco compound which is autoxidizable in alkaline solution and the autoxidation product of which is soluble in the solvent used, in a cycle while alternately 65 oxidizing with gaseous oxygen and reducing again partly with alkali metal amalgam and partly by the well known reduction with hydrogen in the presence of catalysts, the precipitated peroxides being separated between the two operations and 70 the substances removed from the solution being replenished.

4. The process of producing alkali metal peroxides which comprises passing a solution of an alkali alcoholate and of an organic leuco com- 75

pound which is autoxidizable in alkaline solution and the autoxidation product of which is soluble in the solvent used, in a cycle while alternately oxidizing with gaseous oxygen and reducing again partly with alkali metal amalgam and partly with a reducing agent containing no alkali and no alkali metal, the precipitated peroxides being separated between the two operations and the substances removed from the solution being replenished.

10 replenished.

5 The process of producing alkali metal peroxides with a regulated content of active oxygen which comprises passing a solution of an alkali alcoholate and of an organic leuco compound

15 which is autoxidizable in alkaline solution and the autoxidation product of which is soluble in the solvent used, in a cycle while alternately oxidizing with gaseous oxygen and reducing again partly with alkali metal amalgam and partly with

20 a reducing agent containing no alkali and no alkali metal, separating the precipitated peroxides between the two operations and replenishing the substances removed from the solution in which, according to the desired content of active oxygen

25 in the product, up to 8 mols of water are introduced into the circulating solution per each mol of oxygen consumed.

30 6. The process of producing alkali metal per-
oxides with a regulated content of active oxygen
which comprises passing a solution of an alkali
alcoholate and of an organic leuco compound
which is autoxidizable in alkaline solution and
the autoxidation product of which is soluble in
the solvent used, in a cycle while alternately ox-
35 idizing with gaseous oxygen and reducing again
partly with alkali metal amalgam and partly by
the well known reduction with hydrogen in the
presence of catalysts, separating the precipitated
peroxides between the two operations and replen-
40 ishing the substances removed from the solution
in which, according to the desired content of
active oxygen in the product, up to 8 mols of
water are introduced into the circulating solu-
tion per each mol of oxygen consumed.

45 7. The process of producing alkali metal per-
oxides with a regulated content of active oxygen
which comprises passing a solution of an alkali
alcoholate and of an autoxidizable organic leuco
compound of the class consisting of hydrazoben-
50 zene and anthrahydroquinone in a cycle while
alternately oxidizing with gaseous oxygen and
reducing again partly with alkali metal amalgam
and partly with a reducing agent containing no
alkali and no alkali metal, separating the pre-
55 cipitated peroxides between the two operations
and replenishing the substances removed from
the solution in which, according to the desired
content of active oxygen in the product, up to 8
mols of water are introduced into the circulating
60 solution per each mol of oxygen consumed.

8. The process of producing alkali metal peroxides with a regulated content of active oxygen which comprises passing a solution of an alkali alcoholate and of an autoxidizable organic leuco compound of the class consisting of hydrazobenzene and anthrahydroquinone in a cycle while alternately oxidizing with gaseous oxygen and reducing again partly with alkali metal amalgam and partly by the well known reduction with hydrogen in the presence of catalysts, separating the precipitated peroxides between the two operations and replenishing the substances removed from the solution in which, according to the desired content of active oxygen in the product, up to 8 mols of water are introduced into the cir-

culating solution per each mol of oxygen consumed:

9. The process of producing alkali metal peroxides with a regulated content of active oxygen which comprises passing a solution of an alkali alcoholate and of an organic leuco compound which is autoxidizable in alkaline solution and the organic autoxidation product of which is soluble in the solvent used in a cycle while alternately oxidizing with gaseous oxygen and reducing again, separating the precipitated peroxides between the two operations and replenishing the substances removed from the solution, and controlling the content of active oxygen in the product by maintaining a substantial amount of water in the circulating solution and adding up to 8 mols of water per each mol of oxygen. 10 15

10. The process of producing alkali metal peroxides with a regulated content of active oxygen which comprises passing a solution of an alkali alcoholate and of an autoxidizable organic leuco compound of the class consisting of hydrazo-benzene and anthrahydroquinone in a cycle while alternately oxidizing with gaseous oxygen and reducing again, separating the precipitated peroxides between the two operations and replenishing the substances removed from the solution, and controlling the content of active oxygen in the product by maintaining a substantial amount of water in the circulating solution and adding up to 8 mols of water per each mol of oxygen.

11. The process of producing alkali metal peroxides with a regulated content of active oxygen which comprises passing a solution of an alkali alcoholate and of hydrazobenzene in a cycle while alternately oxidizing with gaseous oxygen and reducing again, separating the precipitated peroxides between the two operations and replenishing the substances removed from the solution, and controlling the content of active oxygen in the product by maintaining a substantial amount of water in the circulating solution and adding up to 8 mols of water per each mol of oxygen. 35 40

to 8 mols of water per each mol of oxygen. 45
12. The process of producing alkali metal peroxides with a regulated content of active oxygen which comprises passing a solution of an alkali alcoholate and of an anthrahydroquinone in a cycle while alternately oxidizing with gaseous oxygen and reducing again, separating the precipitated peroxides between the two operations and replenishing the substances removed from the solution, and controlling the content of active oxygen in the product by maintaining a substantial amount of water in the circulating solution and adding up to 8 mols of water per each mol of oxygen. 50 55

13. The process of producing alkali metal peroxides with a regulated content of active oxygen which comprises passing a solution of an alkali alcoholate and of an organic leuco compound which is autoxidizable in alkaline solution and the organic autoxidation product of which is soluble in the solvent used, in a cycle while alternately oxidizing with gaseous oxygen and reducing again with alkali metal amalgam, separating the precipitated peroxides between the two operations and replenishing the substances removed from the solution, and controlling the content of active oxygen in the product by maintaining a substantial amount of water in the circulating solution and adding up to 8 mols of water per each mol of oxygen.

14. The process of producing alkali metal peroxides with a regulated content of active oxygen which comprises passing a solution of an alkali 75

alcoholate and of an autoxidizable organic leuco compound of the class consisting of hydrazobenzene and anthrahydroquinone in a cycle while alternately oxidizing with gaseous oxygen and reducing again with alkali metal amalgam, separating the precipitated peroxides between the two operations and replenishing the substances re-

moved from the solution, and controlling the content of active oxygen in the product by maintaining a substantial amount of water in the circulating solution, and adding up to 8 mols of water per each mol of oxygen.

GEORG PFLEIDERER.
